UNITED STATES PATENT OFFICE.

REGINA MOHRHENN, OF NEW YORK, N. Y.

DESIGN FOR A CASSEROLE.

45,601.

Specification for Design.

Patented Apr. 14, 1914.

Application filed January 24, 1914. Serial No. 814,247. Term of patent 7 years.

To all whom it may concern:

Be it known that I, REGINA MOHRHENN, a subject of the Emperor of Germany, a resident of the city, county, and State of New York, have invented a new, original, and ornamental Design for Casseroles, of which the following is a specification, reference being had to the accompanying drawings, forming part thereof.

The figure is a perspective view of a casserole, showing my new design.

I claim—

The ornamental design for a casserole, as shown.

In testimony whereof, I, affix my signature, in presence of two witnesses.

REGINA MOHRHENN.

Witnesses:

C. B. SCHWEDLER,
M. A. BILL.
